UNITED STATES PATENT OFFICE.

HENRY PEZZETTI, OF PHILADELPHIA, PENNSYLVANIA.

AMBULANCE.

1,275,733.

Specification of Letters Patent. Patented Aug. 13, 1918.

Application filed June 5, 1917. Serial No. 173,038.

To all whom it may concern:

Be it known that I, HENRY PEZZETTI, a citizen of Italy, and a resident of Philadelphia, in the county of Philadelphia and State of Pennsylvania, have invented certain new and useful Improvements in Ambulances, of which the following is a specification.

This invention relates to that class of ambulances, in which a large number of wounded may be transported on stretcher beds with despatch and with as little annoyance to the wounded as possible.

The chief object of my invention is to provide an improved ambulance body adapted to receive stretcher beds from alongside of the ambulance body, to transport and deliver the beds at their destination without in any way disturbing the occupants of the beds from the moment they are placed on the beds.

Another object of my invention is to produce an ambulance capable of containing a large number of wounded in stretchers, which may be carried therein in a systematic, comfortable and sanitary manner, and may be individually loaded into or removed from the vehicle expeditiously and with a minimum of exertion and consequent jar and distress to the wounded.

My invention comprises a body of rectangular box form, capable of being mounted on an ordinary automobile chassis, and having slotted shutters in its sides, which are adapted to open outwardly and upwardly to admit a stretcher bed in a horizontal position longitudinally of the open side of the body, the body being provided interiorly with pivotally supported arms adapted to be swung outwardly to receive or deliver a stretcher bed alongside the body, and means for raising and lowering the stretcher beds as may be necessary.

With the above and related objects in view, my invention comprises the construction, combination and arrangement of parts hereinafter described, an embodiment whereof is illustrated in the accompanying drawings, and is embraced within the scope of the appended claims.

In the said drawings:—Figure 1 is a side elevation of a preferred form of my improved ambulance; Fig. 2 is a perspective view of a stretcher bed adapted to be transported by my ambulance; Fig. 3 is a partial side view of the ambulance, partly broken

away, and showing one stretcher in position interiorly of the ambulance, and another stretcher as it is hoisted alongside the ambulance; Fig. 4 is a cross section through the ambulance body; Fig. 5 shows a detail of the stretcher bed and of a removable handle; Figs. 6, 7 and 8 are side, plan and sectional views of a modified form of my ambulance.

Referring more particularly to the drawings for a detail description of my invention:—10 represents the ambulance body, shown in Figs. 1, 3 and 4, the sides of which are provided with longitudinal openings. 65 11 represents shutters hinged to the body above its openings, each shutter being adapted to swing outwardly into a horizontal position. 12 represents braces adapted to prevent the shutters from closing the openings, 70 said braces being removable to permit of the shutters closing the openings. The openings are of a size to admit of the passing of a stretcher bed in a horizontal and longitudinal position.

Interiorly of the body 10, to the front, back and on the opposite sides of the middle division 13, are mounted brackets 14, keyed on rock shafts 15 to swing, when the shafts are turned, interiorly of the body in position 85 to be held by the stops 16, said brackets being adapted to swing outwardly of the body, when the shafts are turned in an opposite direction, and are provided with lugs 17 adapted to be intercepted by the frame of 90 the body to hold the brackets projected outwardly of the body 10, as at α .

The brackets 14 are arranged in pairs on the opposite sides of an opening opposite a shutter, and are provided with horizontal 95 sockets 18. A stretcher bed 20, mounted on legs 21, is provided with trunnions 22 adapted to be received by the sockets 18, so as to hold a bed suspended between a corresponding pair of brackets 14.

Each bracket is provided with sockets 23, adapted to be engaged by a bar 24, for operating a pair of brackets to carry a stretcher bed from a position outwardly of the body 10 to a position inwardly of said body or the 105 reverse, as shown in Fig. 4.

In order to hoist a stretcher bed from the ground to a position intermediate a pair of brackets, slides 25 movably supported at the top inside the body 10 are adapted to be projected outwardly through an opening, the projecting portions carrying pulleys 26, over

which run ropes or chains 27 adapted for attachment to the trunnions on the opposite sides of a stretcher bed, said ropes being guided by pulleys 29, and are adapted to be wound on drums 30, by a crank 31, whereby a bed is hoisted into the position convenient for the trunnions to enter the sockets of the brackets, as shown by the dotted lines in Fig. 4, the trunnions being provided with recesses for engagement by pins 28 which are suspended from the free ends of the ropes or chains 27. When the slides 25 are inside the body 10, the pins 28 are projected through eyes as shown on the right of Fig. 4, and when the slides are to be projected in position to hoist a stretcher bed, the pins are removed from the eyes, passed through the slots 32 (Fig. 1), and by pulling on the ropes or chains, the slides are pulled through said openings 32, the pins 28, of a corresponding pair of ropes or chains are inserted in the sockets of the opposite trunnions 22 of a stretcher, and the stretcher hoisted alongside a corresponding opening between a pair of brackets 14, and the stretcher swung inside the body of the ambulance by means of a bar 24.

From the above it will be readily understood that the ambulance may be loaded with empty beds, and driven to a convenient position, the beds unloaded and carried by means of the detachable handles 33 close to the wounded, the wounded loaded on the beds and carried alongside the ambulance, the handles removed, the beds with the wounded loaded on the ambulance, the ambulance driven to the base, the beds with the wounded unloaded and carried away by means of the detachable handles, and empty beds reloaded.

In Figs. 6, 7 and 8 is illustrated an ambulance of the above description adapted to accommodate half the number of beds and provided with a central space to accommodate a number of wounded who are able to stand, said space also permitting a nurse or physician to give assistance to such of the wounded as require immediate attention.

The ambulances are provided with steps 34 from which the shutters 11 can be reached, or the steps may be used to carry attendants, orderlies or slightly wounded.

Having thus described my invention, what I claim as new and desire to protect by Letters Patent, is—

1. In combination an ambulance body provided with a side opening, pivoted brackets within said body each having an upwardly opening socket for supporting a swinging stretcher, and a stretcher provided at each end with a centrally located pintle adapted to engage said socket.

2. In an ambulance provided with a side opening, a pair of interconnected brackets pivoted supported on the inside of the body

and adapted to be projected through the opening and upwardly open sockets in said brackets pivoted within the body, and adapted to swing a stretcher directly therein.

3. In an ambulance body provided with a side opening, a pair of interconnected brackets pivoted within the body, and adapted to be projected through the opening, stops for sustaining the brackets in both their inward and outward positions, said brackets having upwardly open sockets for the reception of the pintles of a swinging stretcher.

4. The combination of an ambulance body provided with a side opening and a detachable stretcher carried by the body and adapted to pass through said opening, brackets pivoted within the body for supporting said stretcher and adapted to be turned outwardly to project through the side opening, and means located vertically above each of said brackets for hoisting the stretcher, said means being adapted to be moved out and in, in line with the bracket beneath it.

5. An ambulance body provided with an opening, brackets adapted to project through the opening pivotally supported inside the body, a shaft carrying the brackets, means inside the body to prevent the shaft from turning when the brackets are in a given position inside the body, said brackets being adapted to be held by the body when projected through said opening.

6. In an ambulance body provided with a side opening, a pair of stretcher-supporting brackets pivotally mounted within the body and adapted to be turned outward through said side opening, means for causing said brackets to turn in unison, stops on the body for sustaining said brackets in their inward position, a single socket on each bracket for the reception of a stretcher therebetween and stops on the brackets for contacting with the body and supporting the brackets in their outward position.

7. In combination an ambulance body with side openings in vertical alignment, stretcher supporting brackets pivoted within each end of said openings and adapted to be projected therethrough, a hoist within the body above each vertical line of brackets, and means for sliding said hoist outwardly in the same vertical plane that the bracket beneath it is turned into outward position, whereby stretchers may be hoisted conveniently to said brackets to be readily mounted thereon.

8. In combination an ambulance body with side openings in vertical alignment, a detachable stretcher adapted to be projected through each of said openings, a single pintle on each end of said stretcher, socketed supporting brackets for said pintles and hoisting means within the body in vertical alignment above each supporting bracket and adapted to be projected outside of the body.

to a position vertically above the socket of said bracket when in its outward position, whereby when a stretcher is raised the pintles may be readily entered into said sockets.

9. In combination an ambulance body with side openings in vertical alinement, stretcher supporting brackets pivoted within the ends of said openings adapted to be turned outwardly therethrough, slides within the body

above the vertical lines of brackets and adapted to be moved outwardly of the body in the same plane in which the brackets beneath are turned, pulleys on said slides, and means for retaining the pulleys vertically 15 above the brackets in their outward position whereby stretchers may be hoisted into close relation with the brackets for ready attachment thereto.

HENRY PEZZETTI.

Copies of this patent may be obtained for five cents each, by addressing the "Commissioner of Patents, Washington, D. C."

It is hereby certified that in Letters Patent No. 1,275,733, granted August 13, 1918, upon the application of Henry Pezzetti, of Philadelphia, Pennsylvania, for an improvement in "Ambulances," an error appears in the printed specification requiring correction as follows: Page 2, line 68, claim 2, strike out the words "pivoted within the body, and adapt—" and insert the words *for the reception of the pintles of*; and that the said Letters Patent should be read with this correction therein, that the same may conform to the record of the case in the Patent Office.

Signed and sealed this 17th day of September, A. D., 1918.

[SEAL.]

F. W. H. CLAY,

Acting Commissioner of Patents.

Cl. 21—80.
